CLAIM

The ornamental design for a measuring instrument other than for measuring time, as shown and described.

DESCRIPTION

FIG. 1 is a front elevational view of a measuring instrument other than for measuring time, showing the new design;
FIG. 2 is a rear elevational view thereof;
FIG. 3 is a right-side elevational view thereof;
FIG. 4 is a left-side elevational view thereof;
FIG. 5 is a top plan view thereof;
FIG. 6 is a bottom plan view thereof;
FIG. 7 is a perspective plan view thereof;
FIG. 8 is a reference view showing the article in a state of use.
FIG. 9 is a reference view showing the article in a state of use;
FIG. 10 is a reference view showing a portion of the article in a state of use;
FIG. 11 is a reference view showing a portion of the article in a state of use; and,
FIG. 12 is a reference view showing a portion of the article in a state of use.
